UNITED STATES PATENT OFFICE.

FREDERICK A. PHELPS, OF NEWARK, NEW JERSEY.

MACHINE FOR GRINDING THE TEETH OF GEAR-WHEELS.

946,153.

Specification of Letters Patent. Patented Jan. 11, 1910.

Application filed September 24, 1906. Serial No. 336,081.

To all whom it may concern:

Be it known that I, FREDERICK A. PHELPS, a citizen of the United States, residing in Newark, county of Essex, State of New Jersey, have invented certain new and useful Improvements in Machines for Grinding the Teeth of Gear-Wheels, of which the following is a specification.

This invention relates to machines for grinding gear-wheels having involute or cycloidal teeth.

The objects I have in view are the production of a machine for grinding gear-wheels of this description, and is particularly adapted for grinding gears formed of very hard material such as manganese steel, in which the work will be very accurately done, and at less expense than heretofore.

Further objects lie in the production of a machine which will be simple and formed of but few parts, which can be adjusted for wear, and which can be utilized for grinding gears of different sizes and having differently shaped teeth.

I attain these objects by the mechanism illustrated in the accompanying drawing, in which—

Figure 1 is a front view of a machine embodying my invention, Fig. 2 a plan view of the same; Fig. 3 is a view of two of the controlling cams, and Fig. 4 is a detail view of the operative parts of the improvement.

In all the views, like parts are designated by the same reference characters.

In carrying out my invention I provide a rotary cutter, which is moved through the proper path to develop the tooth by means of a master tooth. Two cutters are preferably employed so as to attack the same tooth upon opposite sides simultaneously. A single master tooth is employed for developing all the teeth in the wheel which is being ground. A machine embodying these features is shown in the accompanying drawings, in which the character 1 represents the main frame of the machine. Upon this frame is a main shaft 2, which is rotated by means of a counter-shaft, pulley and gears shown generally at 3. This main shaft 2 is adapted to reciprocate the work during the grinding operation, and advance the grinding wheel, and index and lock the work-supporting table when a fresh tooth is advanced into position to be ground. The main shaft 2 is shown as provided with a

crank which is adapted to be connected to mechanism to reciprocate the carriage which supports the wheel 4, which is to be ground. Any form of mechanism may be employed for this purpose, but I prefer to use that disclosed in my co-pending application for patent filed May 30, 1906, Serial No. 314,926, although any other suitable mechanism may be employed. The shaft 2 rotates the shafts 5 and 6 by suitable worm gearing shown in dotted lines in Fig. 2. The shaft 5 is adapted to actuate the locking and indexing mechanism of any form, such, for instance, as that shown in my co-pending application above referred to. The shaft 6 is adapted to rotate an auxiliary shaft 7, through spiral gearing. This shaft 7 actuates mechanism for moving the grinding tools in and out from the work, and for actuating the means for displacing the grinding tools after a tooth has been ground.

The grinding tools 8 are shown as formed of disks of abrasive material mounted upon shafts 9, which shafts are provided with pulleys 9^a, with which engage belts (not shown), by means of which the grinders will be suitably rotated, and each shaft is mounted in bearings on a grinding carriage 10. Each of the grinding carriages is adjustably mounted upon a moving table 11 which in turn slides in ways on a movable platform 12, which is capable of movement in ways carried on the main frame 1. The direction of movement of the moving platform 12 is parallel to a line drawn through the center of the tooth which is being ground, and the direction of movement of the tables 11 is at right angles to the direction of movement of the platform 12. As shown in Fig. 2, the centers of the shafts 9 of the grinding tools are at right angles to each other, but this angle may be varied if desired. The carriages 10 are adjustably mounted by being carried in ways upon the tables 11, and suitable means, such as the adjusting screws 13 are provided for moving the carriages in relation to the supporting table 11, so that the grinding tools may be advanced toward the work to compensate for wear. The direction of movement of the grinding carriages 10 in relation to the tables 11 is at right angles to the supporting shafts of the grinding tools.

Each of the tables 11 has an integral arm, which extends inward toward its companion

and the extremity of this arm carries a roller 14. These rollers are adapted to engage upon opposite sides of the master tooth 15, and, by engagement therewith, move the tables 11, and with them the grinding tools so as to properly develop the tooth of the wheel. The master tooth is secured upon a supporting base 16. This base slides upon ways 17, mounted upon the main frame 1. The direction of movement of the base upon the ways is parallel to the center line of the tooth which is being ground. The base 16 carries a roller 18, which engages with a cam 19 carried by the auxiliary shaft 7. A spring 20 engaging between the base 16 and a fixed abutment on the main frame 1, serves to constantly press the roller 18 against the cam 19 and to return the base, and with it the master tooth, to position after it has been moved out of position by the cam 19. Two other cams 21, 21, carried on the extremities of the auxiliary shaft 7, engage with the rollers 22 mounted upon stub shafts carried on slides, which slides are adjustably secured 25 to the platform 12. The cams 21, 21 serve to move the said platform toward and away from the work. These cams 21 are in the form of slots made on the inner face of the disks which constitute the bodies of the 30 cams. A spring 23 connects the two tables 11 so as to constantly keep the rollers 14 in engagement with the master tooth 15. The master tooth, as shown in Fig. 4, is in the form of a plate, secured in position on the base 16 by means of a bolt 24 passing through a slot in the plate so that the position of the plate may be changed in relation to the base, in order to utilize a single master tooth for grinding gear teeth of different 35 depths. The formation of the master tooth is made by a cut-away portion in each side of the plate, each cut-away portion being alike. The tooth proper extends from *a* to *b*, and is shown in the form of involute 40 curves. Beyond each extremity of the tooth the plate is cut away so as to accommodate the roller 14 when the latter is in engagement with the extreme edge of the master tooth. In grinding teeth of different shape than involutes, the curves from *a* to *b* would be 45 correspondingly changed.

The shape of the cams 21 and 19 is shown in Fig. 3. In this embodiment of the invention, the periphery of the cam is divided into thirty-two equal parts. In three of these parts, from *c* to *d*, the cam slot 21 is concentric with its center; from *d* to *e*, three more parts, extend sharply outward toward the periphery. During six parts, from *e* to *f*, it is again concentric with the center. Over the remaining twenty parts, from *f* to *c*, the cam slot gradually approaches the center, so as to arrive at the position it is in at *c*. The cam 19 is shown as concentric for 50 the major portion of its circumference, the

cam protuberance being at about the middle of the space between *c* and *d* extending to slightly beyond the part *d*.

The operation of the machine is as follows: The wheel to be ground is adjusted 70 upon its supporting table, which is properly locked and indexed. The grinding wheels being then rotated in the proper direction and at the correct rate of speed, the main shaft 2 is rotated, which will reciprocate the 75 table carrying the wheel which is being ground, and at the same time, through the intermediary of the shaft 6, the spiral gears will rotate the auxiliary shaft 7. This will rotate the cams 19 and 21. The cams 21, 80 through the agency of the rollers 22 will move the platform 12 toward the center of the wheel which is being ground. The spring 23 will keep the rollers 14 in engagement with the master tooth 15. The latter 85 will be immovably held in position by pressure of the spring 20 engaging the roller 18 upon the concentric part of the cam 19. As the platform 12 is moved toward the wheel which is being ground, and carrying, as it 90 does, the table 11 with it, the rollers 14 on the latter engaging with the inclined walls of the master tooth, will roll on the curved walls of the master tooth and will thereby be separated. As the tables 11 carry the 95 grinding carriages 10 and the grinders thereon, the latter will be separated to the extent determined by the amount of curve and dimensions of the master tooth 15. The cutting edges of the grinders will be accurately moved to follow the contour of the master tooth which will be the shape desired for the finished tooth to assume. This movement of the grinders toward the base of the tooth will continue until the grinders have 100 reached the base of the tooth, which position will be determined by the cams 21. This grinding movement will be caused by the cam 21 moving through the space from *f* to *c*. When the rollers 22 are in engagement 105 with that portion of the cam 21 at the point *c*, the grinding wheels will have been moved to their innermost point of travel and will grind the base of the tooth. The rollers 22 will now engage with that portion of the 110 cam 21 between *c* and *d*, which will hold the platform 12 immovably in position. The roller 18 will then be engaged by the protuberance on the cam 19, which will have the effect of moving the base 16, and with it the 115 master tooth, out against the tension of the spring 20, causing the rollers 14 to roll upon the curved portions of the master tooth beyond the position *a* thereon, at which place the tooth becomes wider. This will have the 120 effect of separating the tables 11, and with them the grinding wheels. This is for the purpose of drawing away the grinders from the work, so that when they are brought out to be in position for grinding a fresh tooth, 125 130

they will not come in contact with the tooth which has been ground. The rollers 22 will then come in contact with that portion of the cam 21 between *d* and *e* which will serve to quickly move the platform 12, and with it the grinding wheels, away from the wheel which is being ground. At the same time, the cam 19 turning, will disengage its protuberance from the roller 18, allowing the spring 20 to move the base 16 and master tooth into their normal positions. During the movement of the cam 21 from *e* to *f*, the grinders will be held out and away from the wheel which is being ground, while the latter is being rotated to advance a fresh tooth to be acted upon by the grinders.

From the mechanism described, it will be seen that the tooth is simultaneously attacked on both sides so that it will be completed in one operation. This does not require therefore that the wheel be re-adjusted or turned over upon its supporting platform after one side of the tooth has been ground. It will also be seen that by employing a single master tooth, much greater accuracy can be secured than where the master tooth is in the form of a complete wheel, or a segment thereof, having a number of teeth. Also, it will be seen that by employing a single master tooth, the latter can be utilized for grinding wheels of different sizes and with different sized teeth. It will also be seen that by employing a single master tooth it is possible to utilize the rollers 14, as they do not have to engage between successive teeth, but only on one side of the single tooth; consequently the wear upon the faces of the master tooth is reduced to a minimum.

By employing grinding tools which engage at the edges, as distinguished from grinding tools which engage at one face, the adjustment of the machine is not changed by wear of the tool. It is sufficient to adjust the position of the grinding carriages 10 upon the tables 11 to make up for

wear; the shape of the tooth will not be changed by the wear of the grinding tool.

While I have disclosed my invention as applied to a machine for grinding gear-wheels, it is obvious that it may be used in grinding devices employing teeth contradistinguished from wheels, such as segments, racks, etc.

In accordance with the provisions of the patent statute, I have described the principle of operation of my invention, together with those embodiments which I now consider to be the best means of carrying out my invention, but I desire to point out that such means are merely illustrative and that the invention may be carried out by other means than those shown.

Having now described my invention, what I claim as new and desire to secure by Letters Patent is:

1. A machine for grinding the teeth of gear-wheels, the combination of a master and a grinder, the said master being adjustably mounted for different sized teeth.

2. A machine for grinding the teeth of gear-wheels having a single master tooth which is an exact duplicate of the tooth which is to be produced; the said master having an extension to open the grinder on the return stroke.

3. A machine for grinding gear-wheels, having a master tooth with an extension thereon.

4. A machine for grinding gear-wheels, having a master tooth with an extension thereon, and means to advance the master tooth after the tooth is ground to move the grinders away from the work on the return stroke.

This specification signed and witnessed this nineteenth day of September, 1906.

FREDERICK A. PHELPS.
